UNITED STATES PATENT OFFICE.

LAWRENCE H. WALKER, OF MUSKEGON, MICHIGAN, ASSIGNOR TO THE SHAW WALKER COMPANY, OF MUSKEGON, MICHIGAN, A CORPORATION OF MICHIGAN.

DRAWER-GUIDE.

No. 874,463.

Specification of Letters Patent.

Patented Dec. 24, 1907.

Application filed March 23, 1907. Serial No. 364,012.

To all whom it may concern:

Be it known that I, LAWRENCE H. WALKER, a citizen of the United States of America, residing at Muskegon, in the county of 5 Muskegon and State of Michigan, have invented certain new and useful Improvements in Drawer-Guides; and I do hereby declare the following to be a full, clear, and exact description of the invention, such as 10 will enable others skilled in the art to which it appertains to make and use the same.

My invention relates to improvements in drawer guides and its object is to provide a strong and easily operated device, to provide 15 for readily detaching the drawer from the guides, and to provide the same with various new and useful features hereinafter more fully described and particularly pointed out in the claims.

20 My invention relates more particularly to guides for the drawers of vertical filing cabinets, and consists essentially of ways fixed in the case and having bottom and side grooves, slides having wheels engaging the 25 bottom grooves, a drawer supported upon the slides, wheels supporting the rear end of the drawer and traversing the side grooves of the ways, and in various features of construction and arrangement as will more fully 30 appear by reference to the accompanying drawings, in which:

Figure 1. is a side elevation of a device embodying my invention showing the drawer fully extended from the case; Fig. 2. a longitudinal vertical section of the case with the 35 drawer shown in broken lines within the same and the other parts in position as when the drawer is within the case; Fig. 3. a transverse section on the line 3—3 of Fig. 2.; Fig. 4. the same on the line 4—4 of Fig. 1.; Fig. 5. a perspective detail of one of the 40 slides; and Fig. 6. a detail in plan view of one of the slide supporting rolls.

Like numbers refer to like parts in all of 45 the figures.

1 represents a case and 2 a drawer to fit within the same, these being of any convenient dimensions and construction, those shown being adapted for a vertical filing 50 case. At each side of the drawer and supporting the front of the same are slides 3 longitudinally movable between the drawer and the case and adapted to extend to about the middle of the drawer when both are 55 drawn out from the case. These slides 3 at

the rear end are vertically extended to the under side of the ways and to leave a space between the narrower front portions of the slides and the ways to accommodate the supporting wheels 6 on the respective sides of 60 the drawer and near the middle thereof. These wheels 6 traverse the upper edge of the narrow portion of the slides and support the front of the drawer. The wheels 6 are also mounted in casings 7 secured to the 65 sides of the drawer and having downwardly extended outer sides 7^a, which engage and traverse outer sides of the slides within the rabbets 8. Above the slides and fixed in the case are ways 4 each having a groove 12 in 70 the under edge traversed by a wheel 10 journaled in the rear upper corner of the slide 3, which wheel serves to guide and hold down the inner end of the slide and also to stop the same in its outward movement by contact 75 with the outer end of the groove as at 12^a, which groove terminates at a proper point to limit this outward movement of the slide, so that the drawer will stop with its inner end slightly within the case. In the inner 80 sides of the ways 4 are other grooves 11 in which and traversing the same are wheels 5 journaled on the sides and near the rear end of the drawer, and supporting the same. These grooves are open at the front end, 85 whereby the wheels are readily detached therefrom as occasion may require.

On the outer end of each slide 3 is a stop 13 preferably of elastic material to limit the outward traversing of the wheel 6 by engagement of this stop with the case 7.

14 is an elastic buffer on the end of the slide, which engages the front of the drawer when the same is moved inward and 15 a similar buffer on the rear of each slide to engage the back of the case. These elastic stops and buffers thus prevent noise and shock when the device is operated. To support the slides 3 and permit the same to move freely, rolls 9 are provided in the bottom of the case at the front thereof and beneath the slides, which rolls are located in recesses in the bottom of the case and journaled on a rod 17 inserted in a transverse groove 16 in the case. The wheels 6 on the 105 sides of the drawer being located near the middle thereof carry the greater portion of the load and the wheels 5 serve to carry the remainder and support the rear end of the drawer. To remove the drawer from the 110

case, it is only necessary to raise the front end sufficient to carry the cases 7 over the stops 13, the drawer can then be carried outward and the wheels 5 removed from the front ends of the grooves 11 in the ways. The drawer can be readily replaced by a reverse operation. To detach the slides after the drawer has been removed, it is only necessary to move the lower edges of the same inward until the wheels 10 are removed from the grooves 12 in the ways 4.

What I claim is:

1. The combination of a case, ways fixed on the sides of the case, slides longitudinally movable between the ways and the bottom of the case and guided thereby, a drawer movably supported near the middle by the slides, and means for movably supporting the rear end of the drawer upon the ways.
2. The combination of a case, ways fixed on the sides of the case and having grooves in their lower edges, slides longitudinally movable beneath the ways, wheels journaled near the rear upper corners of the slides and traversing the grooves, a drawer movably supported near the middle by the slides, and means for movably supporting the rear end of the drawer on the ways.
3. The combination of a case, ways fixed on the sides of the case and having grooves in their inner sides, slides longitudinally movable between the ways and the bottom of the case and guided thereby, a drawer movably supported near the middle on the slides, and wheels journaled on the sides of the drawer near the rear thereof and traversing the grooves in the ways.
4. The combination of a case, ways fixed on the sides of the case and having grooves in their lower edges and grooves in their inner sides, slides longitudinally movable beneath the ways, wheels journaled on the rear ends of the slides and traversing the grooves in the lower edges of the ways, a drawer, wheels on the sides of the drawer near the middle thereof and traversing the upper edges of the slides, and wheels on the sides of the drawer near the rear thereof and traversing the grooves in the inner sides of the ways.
5. The combination of a case, ways fixed on the sides of the case and having grooves in their lower edges and grooves in their inner sides, slides longitudinally movable beneath the ways and having vertically reduced forward ends, wheels journaled on the rear ends of the slides and traversing the grooves in the under edges of the ways, a drawer, wheels on the sides of the drawer and traversing the grooves in the inner sides of the ways; wheels on the sides of the drawer trav-

ersing the upper edges of the forward ends of the slides, and casings for the last named wheels, said casings having downwardly projecting outer sides slidably engaging the outer sides of the slides.

6. The combination of a case, ways fixed on the sides of the case, slides longitudinally movable between the ways and the bottom of the case and guided thereby, said slides having vertically reduced forward portions provided with rabbeted outer sides, a drawer, wheels on the sides of the drawer near the middle thereof and traversing the upper edge of the forward part of the slides, casings for said wheels, said casings having downwardly projecting outer sides extending into and traversing the rabbets in the slides, stops on the ends of the slides to engage the casings, and means for movably supporting and guiding the rear of the drawer by means of the ways.

7. The combination of a case, ways fixed on the sides of the case and having grooves in the rear portion of their lower edges only, and grooves in their inner sides open at the front end, slides longitudinally movable beneath the ways, wheels journaled on the rear ends of the slides and traversing the grooves in the lower edges of the ways and stopped by the front ends of said grooves, a drawer movably supported upon the front ends of the slides, and wheels journaled on the sides of the drawer near the rear thereof and traversing the grooves in the inner sides of the ways and freely removable from the front ends thereof.

8. The combination of a case, a drawer in the case, ways fixed on the sides of the case, and having grooves in their lower edges and also having grooves in their inner sides, the edge grooves terminating at a distance from the front and extending rearward and the side grooves open at the front, slides beneath the ways and having vertically reduced and rabbeted forward ends, wheels journaled on the slides and traversing the grooves in the lower edges of the ways, wheels on the drawer and traversing the grooves in the sides of the ways, wheels on the drawer and traversing the reduced upper edges of the forward ends of the slides, and cases for the last named wheels having downwardly extended outer sides traversing the rabbets of the slides.

In testimony whereof I affix my signature in presence of two witnesses.

LAWRENCE H. WALKER.
